UNITED STATES PATENT OFFICE.

NATHANIEL EATON, OF MOUNT VERNON, NEW YORK.

RAILROAD-SWITCH.

SPECIFICATION forming part of Letters Patent No. 253,271, dated February 7, 1882.

Application filed April 9, 1881. (No model.)

To all whom it may concern:

Be it known that I, NATHANIEL EATON, of Mount Vernon, county of Westchester, in the State of New York, have invented a new and Improved Railroad-Switch; and I do hereby declare that the following is a full and exact description thereof, reference being had to the accompanying drawings, and to the letters of reference marked thereon, making a part of this specification.

Figure 1 is a plan view of my device. Figs. 2, 3, 4, 5, and 6 are views in detail.

A A are rails of main track; B B, rails of side track; C C, switch-rails; D D, rails of main track beyond the switch; E, cross-bar to move switch and also lock it; H, lever to move switch; I, lever to move switch through lever H; K, a lever to raise and move the upper end of lever I out of connection with lever H when a train is to be let into the siding B B. This lever is made to slide forward and back in the socket L, as required, by the movement of lever I, made by the train passing onto the side track. Said lever K rests in socket L for a fulcrum to enable the switch-tender or any other person, by bearing down the end outside the track, to lift the end of lever I out of connection with the lever H. The passing of the locomotive or car onto the switch will move the lever I, and that will move lever K. The latter, therefore, is made to slide sufficiently on its fulcrum L for that purpose. This lever K is not fastened in any way, because it is intended that the switch-tender shall always drop the lever I into place, after a train has passed onto a side track, before he leaves it. If he did not hold it until the train passed, he might leave it and then forget to put it in order. L is a socket for lever K to get a bearing; M, pivot which connects cross-bar E with lever H; N, pivot which connects lever H with cross-bar G; O, pivot on which lever H turns; P, pivot on which lever I turns; Q, socket in which the lower end of lever I slides; S S S, bars to hold switch-rails C C together; W, ties on which the rails are laid; Y, block with open end to receive catch on under side of bar E; Z, block with notch for sides of lever H to bear against when moved to either side.

When a train is to be let on the side-track rails B B the switch-tender, with the cross-bar E, moves the switch-rails C C to meet the side-track rails B B. This forces the lever H to move the lever I, and the outer end of it goes

snug against one rail, D, of the main track. 55 Then the switch-tender, with the lever K, raises and holds the upper end of lever I out of connection with lever H until the train passes onto the side-track rails B B, then he lets it drop into its place. Should a train 60 come on the main-track rails D D before the switch is replaced the flange of the engine-wheel would force the lever I (through lever H) to move the switch into connection with the main-track rails A A and pass safely over. 65 The levers H and I are long enough to move the switch before the engine or locomotive reaches it. I lock it by a projection on cross-bar E playing into a notch in block Y. The levers H and I are disengaged, but play into 70 each other when lying horizontally flat on the ties between the switch-rails C C and the main-track rails D D, and reach from the free ends of the switch-rails C C to the ends of one length of the main-track rails D D, which are 75 adjacent to the pivoted ends of switch-rails C C.

It will be observed in Fig. 1 on the annexed drawings that when the switch rails C C are in coincidence with the main-track rails A A a 80 passing train does not touch the levers H and I or move the switch-rails C C. I hang my levers H and I on pivots about two-thirds the distance from their heads, or so far as to give them the sweep to move the switch-head from 85 the side track B B to the main-track rails A A by the flange of the wheel of the engine pressing on the lever I at its base or junction with the rails of the main track D D. This forces cross-bar E and its projection back past the 90 beveled catch.

What I claim, and wish to secure by Letters Patent, is—

In an automatic railroad-switch, the combination of horizontal levers H and I, switch-rails C C, and cross-bar G, pivoted to lever H, 95 said parts being adapted to be moved by the flanges of the wheels of passing locomotives or cars striking one of said levers, the levers H and I being adapted at their meeting ends 100 to be disconnected to direct a train upon the siding, all substantially as shown and described.

NATHANIEL EATON.
